[57] CLAIM

The ornamental design for a video camera wall mounting bracket, as shown and described.

DESCRIPTION

FIG. 1 is a front elevation view showing our new design;

FIG. 2 is a left side elevation view thereof;

FIG. 3 is a bottom plan view thereof;

FIG. 4 is a rear elevation view thereof;

FIG. 5 is a right side elevation view thereof;

FIG. 6 is a top plan view thereof;

FIG. 7 is a left front perspective view thereof;

FIG. 8 is a right rear perspective view thereof; and,

FIG. 9 is a perspective view of the interior portion of the claimed design detached from the main housing. This element has been shown separately for clarity of illustration.
